FOUNTAIN COMB

Percy Bankston, Crossville, Tenn.

Application June 1, 1938, Serial No. 211,226

2 Claims. (Cl. 132—13)

This invention relates to a fountain comb, the general object of the invention being to provide the comb with a reservoir at its upper portion for receiving various kinds of solutions for the treatment of the scalp, with manually controlled means for causing some of the solution to pass from the reservoir to the tooth carrying edge of the comb.

This invention also consists in certain other features of construction and in the combination 10 and arrangement of the several parts to be hereinafter fully described, illustrated in the accompanying drawing and specifically pointed out in the appended claims.

In describing the invention in detail, reference 15 will be had to the accompanying drawing wherein like characters denote like or corresponding parts throughout the several views, and in which:

Figure 1 is an elevation of the improved comb.

Figure 2 is a section on the line 2—2 of Figure 1.

Figure 3 is an enlarged fragmentary vertical sectional view showing the valve means.

In this drawing the letter A indicates the comb and the letter B indicates the reservoir the lower edge of which is connected with the upper edge of the comb in any suitable manner. One end portion of the reservoir is made of greater height than the rest of the reservoir and this high part is formed with the two spaced upwardly extending parts 1, preferably shaped as shown, these parts forming a recess 2, the bottom of which is formed with an opening 3 closed by a cork 4 which is cemented in place. Below the recess the comb is formed with an opening 5 in which is cemented a cork 6 which has a longitudinally extending hole or bore 7 therein which leads from the reservoir through the lower edge of the body of the comb.

A plate 8 extends across the bottom of the recess 2 and across the top of the cork 4. A valve rod 9 passes through a hole in the plate 8 and through a hole in the cork 4 and said rod also passes through the bore 7 of the cork 6 and has a valve disk 10 at its lower end for closing the lower end 45 of the bore 7. The upper end of the rod extends above the plate 8 but terminates short of the plane of the top part of the portions 1 so that these parts 1 prevent the valve rod being depressed to open the valve 10 by accident, such as 50 the upper part of the reservoir being struck by an object or pressed against an object. A button 11 is connected with the upper end of the valve rod for facilitating the depression of the rod and a spring 12 encircles the upper portion of the rod 55 and has one end bearing against the button 11

and the other against the plate 8. A small cylinder 13 is located in the space between the two corks and the valve rod passes through the cylinder. The valve rod carries a piston 14 of leather or the like which operates in the cylinder and the upper open end of the cylinder is formed with the notches 15 and its lower end is outwardly bowed as shown at 16 and provided with a central port 16' through which the valve rod 9 extends, said port 16' being slightly larger than the rod 9 10 for a purpose presently seen. This ported end 16 is spaced from the cork 6 when the upper end of the piston is engaging the cork 4 and in axial alignment with the bore 7.

A filling opening is formed in a part of the 15 reservoir and is closed by a plug 17 so that by removing the plug, tonic or other solutions can be placed in the reservoir and then the plug is closed. Then when it is desired to place some of the solution on the scalp the user presses upon the button 11 to lower the valve rod 9 which opens the valve 10 and on the first part of the downward movement of the stem the frictional engagement of the piston 14 with the cylinder 13 will cause the cylinder to move downwardly until its lower ported end 16 rests upon the cork 6 with the port 16' registering with the bore 7. Then further downward movement of the valve rod will cause the piston 14 to eject some of the solution in the cylinder through the port 7 and past the valve 10 upon the scalp or other part of the body over which the comb is being drawn. Then when the button is released the spring 12 returns the parts to the normal position and on the first part of this upward movement of the valve rod the cylinder 13 will move upwardly with the piston 14 until its notched end strikes the cork 4 when further movement of the cylinder will be prevented and then as the valve rod continues its upward movement the piston 14 will draw some of the solution into the bottom of the cylinder through the port 16'. Of course, the notches 15 prevent air being trapped in the top of the cylinder by the piston.

The teeth of the comb at the point where the opening 5 is formed are spaced a greater distance apart than are the other teeth and these two teeth are made larger as shown at 18 to protect the smaller teeth when the device is being used to apply solution to the scalp or other part of the body.

While I prefer to use corks 4 and 6 for closing the upper and lower openings it will, of course, be understood that any other suitable material can be used for these members and such mem- 55

bers can be of resilient material so that the valve plate 10 will make a fluid tight joint with the lower end of the member 6 and the stem will have a sliding fluid tight passage through 5 the upper member 4. The plate 8, of course, prevents the spring from embedding itself into the top part of the member 4.

As will now be seen, I have provided a fluid measuring cylinder 13 endwise movable in the 10 reservoir B in opposite directions, respectively, under similar movement of the valve rod 9 and between opposite limits of movement established by engagement thereof with the corks 4 and 6, the ported end 16 of the cylinder being opposed to the 15 bore 7 in one limit of movement of said cylinder so as to block communication between said bore and the reservoir B and so as to provide for ejection of the measured amount of fluid from the cylinder through said bore under the action of 20 the piston 14, the ported end 16 of said cylinder being spaced from said bore 7 in the other limit of movement of the cylinder for the filling of the cylinder through the port 16' with a uniform 25 amount of fluid each time the valve rod 9 and piston 14 are operated by the spring 12.

It is thought from the foregoing description that the advantages and novel features of the invention will be readily apparent.

It is to be understood that changes may be 30 made in the construction and in the combination and arrangement of the several parts provided that such changes fall within the scope of the appended claims.

Having described the invention, what is claimed 35 as new is:

1. A fountain comb comprising a back having a toothed edge and a discharge duct extending therethrough for conveying liquid to said edge, a liquid-containing reservoir on said back with 40 which said duct communicates, and means to eject a measured amount of liquid out of said duct comprising a liquid-measuring cylinder endwise movable in the reservoir between opposite limits of movement and having a ported end opposed to said duct in one limit of movement of said cylinder to block communication between said duct and reservoir and provide for ejection of 45 fluid into the duct directly from said cylinder,

said ported end in the opposite limit of movement of the cylinder being spaced from said duct for the filling of the cylinder therethrough from the reservoir, and a plunger extending into said reservoir and cylinder, said plunger being manipulative inwardly of the cylinder to move the same into the first-mentioned limit of movement thereof and subsequently eject the fluid therefrom through said ported end and into said duct, and being tensioned for movement outwardly of said cylinder to move the latter into said opposite limit of movement thereof and subsequently draw fluid from the reservoir into the cylinder by way of the ported end of the latter.

2. A fountain comb comprising a back having a toothed edge and a discharge duct extending therethrough for conveying liquid to said edge, a liquid-containing reservoir on said back with which said duct communicates, and means to eject a measured amount of liquid out of said duct comprising a liquid-measuring cylinder endwise movable in the reservoir between opposite limits of movement and having a ported end opposed to said duct in one limit of movement of said cylinder to block communication between said duct and reservoir and provide for ejection of fluid into the duct directly from said cylinder, said ported end in the opposite limit of movement of the cylinder being spaced from said duct for the filling of the cylinder therethrough from the reservoir, and a plunger extending into said reservoir and cylinder, said plunger being manipulative inwardly of the cylinder to move the same into the first-mentioned limit of movement thereof and subsequently eject the fluid therefrom through said ported end and into said duct, and being tensioned for movement outwardly of said cylinder to move the latter into said opposite limit of movement thereof and subsequently draw fluid from the reservoir into the cylinder by way of the ported end of the latter, said plunger extending through said duct and having an enlarged end coacting with said back to establish an outward limit of movement of the plunger and simultaneously close the outer end of the duct to prevent leakage of the fluid therefrom.

PERCY BANKSTON.
